CLAIM

The ornamental design for a walkie talkie, as shown and described.

DESCRIPTION

FIG. 1 is a front perspective view of a walkie talkie according to the present invention;

FIG. 2 is a rear perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is an enlarged top side view thereof; and,

FIG. 8 is an enlarged bottom side view thereof.

The broken lines shown in the figures are for the purpose of illustrating portions of the walkie talkie, which form no part of the claimed design.
